Patented Aug. 2, 1921.

INVENTOR.

Enoch J. Blackmon.

WITNESS.

P. O. Pederson.

UNITED STATES PATENT OFFICE.

ENOCH J. BLACKMON, OF SHERMAN, TEXAS.

HIGH-PRESSURE SUCTION FAN AND BLOWER.

1,386,548.

Specification of Letters Patent.

Patented Aug. 2, 1921.

Application filed December 9, 1920. Serial No. 429,576.

To all whom it may concern:

Be it known that I, ENOCH J. BLACKMON, a citizen of the United States, residing at Sherman, in the county of Grayson and State of Texas, have invented certain new and useful Improvements in High-Pressure Suction Fans and Blowers, of which the following is a specification.

This invention relates to high pressure suction fan and blower, and may be used either in conjunction with a cotton gin to increase the suction for handling cotton from bin or wagon, or it may be used for any other purpose where suction or blast fans are used. The agencies employed in performing the functions of the present construction are mechanical and carried out by means of an inner and an outer casing whereby the air entering the fan at the side 10 is forced by the fan wings through the openings of the inner wall of the cylindrical chamber formed of inclined vanes, and passes through the vanes to the outer chamber, then to a discharge flue extending from 15 the outer casing of the fan.

By the special construction of parts hereinafter described and claimed, as well as by the general combination, arrangement and co-operation of the elements entering 20 into the machine as a whole, I have devised a fan which will operate in a continuous and highly efficient manner and increase the air pressure with a reduced power of operation.

In the accompanying drawings which 25 serve to illustrate this invention more fully, Figure 1, is a side elevation, a portion being broken away to disclose interior mechanism. Fig. 2 is a plan view partly in section through the line X X of Fig. 1, and 30 with portions broken away to clearly show more important interior features.

In the embodiment of the invention shown in the drawings 1 represents a suction fan or blower having a circular opening 2 in the front side 3, over which opening is bolted a plate 4, provided with an opening 5 that is connected through the usual conveyer trunk (not shown). The fan 1 is equipped with a rotor comprising a disk 6 secured 45 to the edges of fan wings 7, all mounted on a shaft 8 that is supported in the usual bearings 9, and may be driven from any convenient point by belt 10. The wings 7 are

not as wide as the interior width of the fan casing, and each has a curve 11 on its outer edge to prevent any substance from hanging on same. A cylindrical wall is formed within the fan casing by a plurality of laterally disposed, inwardly inclined metal vanes 12, spaced apart and secured to the sides of the casing in any suitable manner, said wall forming a cylindrical chamber 13 in which the fan revolves. The air blast is forced between the edges of these vanes to the out chamber of the fan casing giving it an increased pressure as the air is taken from the fan wings at a close range without forming back pressure or vacuum around the fan. The air passing around the outer chamber 14 is evenly increased by the air passing between the vanes that form the inner casing and around the fan to the discharge flue; a valve 15 suitable to release any substance that is drawn into the chamber 13 that will not pass between the edges 55 of the vanes, is placed over the discharge flue of the fan in wall 12 with weight 16 for closing same.

From the foregoing description it will be seen that I provide a suction fan and blowing machine that is exceedingly simple in construction and efficient in operation, and while I have shown and described a specific embodiment of means for carrying the principles of my invention into practical operation, I desire it to be understood that the specific form shown, while the best form in which I at present contemplate carrying my invention into practical operation, is merely illustrative of an operative embodiment of practical means, and I do not limit or confine myself thereto.

Having now set forth the object and nature of my invention and a form of apparatus embodying the same and having described the construction, function, and mode of operation thereof, what I claim as new and desire to secure by Letters Patent, is—

1. A device of the class described comprising a fan casing, a circular wall within the casing formed of transversely disposed inclined vanes supported by the sides of said casing and forming a cylindrical chamber, a fan positioned in said chamber, a deflector valve disposed in the chamber adjacent to the cylindrical wall.

2. In a machine of the class described, in combination with a fan casing and a fan positioned therein, a serrated circular wall formed of vanes spaced apart for the passage of air, and positioned exterior of the fan, dividing the intervening space between the fan and the outer shell of the casing into

an inner and an outer cylindrical chamber, an opening through the wall and deflector valve, for the passage of trash from the inner chamber, the outer chamber of the fan conducting and passing the trash to the exhaust of the fan. 10

ENOCH J. BLACKMON.
